(57) **CLAIM**

The ornamental design for cosmetics container, as shown and described.

DESCRIPTION

FIG. 1 is a perspective view of cosmetics container showing our new design when expanded;

FIG. 2 is a front elevational view thereof when expanded;

FIG. 3 is a rear elevational view thereof when expanded;

FIG. 4 is a left side elevational view thereof when expanded;

FIG. 5 is a right side elevational view thereof when expanded;

FIG. 6 is a top plan view thereof when expanded;

FIG. 7 is a bottom plan view thereof when expanded; and,

FIG. 8 is a reference drawing thereof when retracted.

The broken lines illustrate the cosmetic container's interior ribbing, bottom pivot, tray interiors, and the unshaded structure within the tray interiors. None of the broken lines forms part of the claimed design.
